CLAIM

The ornamental design for a coring spoon, as shown and described.

DESCRIPTION

FIG. 1 is a top view of a coring spoon showing my new design;

FIG. 2 is a bottom view thereof;

FIG. 3 is a front view thereof;

FIG. 4 is a rear view thereof;

FIG. 5 is a left view thereof;

FIG. 6 is a right view thereof;

FIG. 7 is a left-side top perspective view thereof; and,

FIG. 8 is a right-side top perspective view thereof.

The broken lines in the drawings depict portions of a coring spoon that form no part of the claimed design. The dash-dot-dash broken lines represent boundaries that form no part of the claimed design.
